ABRAHAM M. HERBSMAN, OF HUNTINGTON PARK, CALIFORNIA

METHOD OF TREATING COLLOIDS

Application filed April 15, 1929. Serial No. 355,363.

My invention relates to the coagulating or breaking up of suspensions and colloids by the use of rays of short wave-length.

It is frequently desirable to effect the separation of the phases of a chemical system by a coagulation thereof, whereby the coagulated phases may be subsequently separated by suitable treatment. Such coagulation is commonly carried out by the addition to 10 the chemical system of certain chemicals, or by the application of heat thereto. With certain types of chemical systems, such as colloids and suspensions, it is sometimes possible to separate at least certain of the constituents, hereinafter termed the phases, by the use of heat, the application of chemicals by filtering, or by the use of other media. Certain chemical systems respond to treatment with one or more of these media, and 20 other systems are favorably acted upon by the action of an electric field, or by electrolysis, or other electrical phenomena.

My invention relates, however, to the separation of the phases of a chemical system 25 by the use of rays of short wave-length which I have found to be very effective in coagulating or agglomerating the material forming one or more of these phases. My experience has shown that best results are obtained by 30 the use of violet or ultra-violet rays, X-rays, cathode rays, or canal rays. In addition, it is possible to use the alpha, beta, or gamma rays given off by radioactive substances, either in themselves or in conjunction with 35 other rays of short wave-length.

It is an object of this invention to provide a novel method of and apparatus for coagulating or breaking up suspensions or colloids by subjecting these colloids or suspensions to the action of rays of short wave-length.

A further object of this invention is to subject a stream of the substance forming a chemical system to the action of rays of short 45 wave-length, and to subsequently remove this stream from the influence of the rays and separate the coagulated or coalesced phases from each other.

Further objects of this invention reside in 50 the novel processes whereby specific chemi-

cal systems are subjected to the action of rays of short wave-length, and particularly to a method of separating the phases of an emulsion by the use of such rays.

For instance, very effective results have 55 been obtained by subjecting a petroleum emulsion, such as is commonly pumped from an oil-well, to the influence of rays of short wave-length, these rays agglomerating the particles of the dispersed phases, usually 60 water, into globules of sufficient size to gravitate from the oil forming the continuous phase. This treated emulsion is allowed to separate gravitationally by passing it into a suitable settling chamber. An apparatus for 65 carrying out this process is disclosed in Fig. 1.

My invention is applicable to various types of colloids, and by this term I include dispersoids, and colloidal solutions, as will be 70 hereinafter explained. It is, of course, impossible to cite all uses of my process, but typical uses will be illustrated without in any way limiting myself thereto.

Colloids in general may be classed in five 75 types, the first being the chemical system in which a solid and a liquid form respectively the dispersed phase and the dispersion medium, or continuous phase. This type includes, for instance, metals in the colloidal state, and one use of my process is for coagulating colloidal gold or other metal in 80 such a colloidal state.

A second type of colloid may have dissimilar liquids comprising the dispersed phase and the dispersion medium, such a type being 85 illustrated by emulsions. My process finds a particular utility in the treatment of emulsions, for by subjecting these emulsions to the action of rays of short wave-length, the dispersed phase is coagulated or agglomerated, 90 as previously explained.

The third type of colloid may comprise a chemical system wherein a gas comprises the dispersed phase and a liquid the dispersion 95 medium, an example being that of the formation of foam. My process may be utilized now only for breaking up a foam such as is commonly formed in different chemical processes, but may also be utilized for preventing 100 any of this foam from forming by utilizing

the rays of short wave-length in conjunction with the other chemical process which normally tends to form foam.

The fourth type of colloids may comprise a chemical system wherein a solid and a gas are intermixed, the solid being the dispersed phase and the gas the dispersion medium, as illustrated most commonly in the formation of smoke. When smoke is subjected to the action of rays of short wave-length, coagulation takes place permitting the separation of the solid and gaseous particles.

Still another, and in our present classification, the fifth type of colloid, may comprise a liquid as the dispersed phase and a gas as the dispersion medium. A common illustration is the formation of clouds, either in the atmosphere or during the performance of certain chemical processes. In the latter instance my invention is particularly applicable, inasmuch as such clouds may be coagulated by subjection to the action of rays of short wave-length.

I have found that possibly the best method of treating all of these types of colloids is to move them in a continuous stream past the source of the rays so that the rays act upon the colloids for a length of time determined, of course, by the particular colloid being treated, after which the treated colloids may be passed to a suitable settling chamber wherein the coagulated or agglomerated phases may separate. Such a separation ordinarily takes place by gravity, as illustrated, for instance, when petroleum emulsion is subjected to the action of the rays and subsequently passed into a settling chamber, the oil phase rising to the top and the water phase dropping to the bottom, due to a difference in density between the material constituting these phases.

I am not limited to any particular method of forming the rays of short wave-length, inasmuch as various means of generating these rays are known to the art. Ultra-violet rays may, for instance, be generated by certain illuminating means such as the carbon arc, X-rays may be derived from the well-known X-ray tube, and the cathode rays may be developed from commercially available tubes. Most of these methods of artificially creating the rays utilize a container so that the source of these rays may properly be said to be inside this container. It thus becomes possible to place or move the material to be treated in contact with the source, or separated therefrom.

In utilizing an ordinary X-ray bulb, the bulb may be placed in the path of travel of the material, thus insuring that the material will be subjected to the maximum intensity of rays. If contact between the source and the material is not desired, this is not necessary, but ordinarily correspondingly stronger rays must be utilized. Certain of these rays

may be utilized in conjunction with reflectors for increasing the intensity of the rays to which the material is subjected. Such reflectors may be polished metal, quartz mirrors, ray-transmitting glass mirrors, or mirrors having a radioactive substance as a backing for quartz or other ray-transmitting glass. Similarly, the reflectors may be made entirely of a radioactive substance or may be coated on the front surface thereof, so that this radioactive substance acts directly in conjunction with the X-rays, ultra-violet rays, cathode rays, or other rays in effectively treating the material.

In some instances it is desirable that only a thin film of the substance to be treated be affected by the rays at any particular instant. All materials act to some extent to impede the passage of these rays, and by forming a thin film of the material, it becomes possible to completely treat this film.

Still a further method of bringing a material to be treated under the influence of the rays is to atomize or finely divide the material and introduce this material in its subdivided state as a mist or in the form of droplets into a chamber containing rays of short wave-length emitted from a suitable source. The particular method will, of course, depend upon circumstances and upon the material being treated and no general rule can be given for all colloids.

It is also possible, and in some cases desirable, to apply heat during the time that the material to be treated is under the influence of the rays of short wave-length, or to preheat this material before thus influenced. My invention should thus not be limited to coagulation without heat, but should be interpreted to include the application of heat either before or during treatment of the material for the purpose of increasing the treating action taking place.

As a practical example of my process, I have illustrated in the drawing one form of apparatus, and will particularly describe this apparatus as used in the separation of the phases of a petroleum emulsion.

Referring to the drawing, I have shown a table 1 having an inclined surface 2 adapted to receive a relatively shallow stream of the emulsion to be treated. This emulsion is discharged from a pipe 3 and impinges against a barrier 4 or other spreading means which will uniformly distribute the emulsion over the inclined surface 2. This shallow stream of emulsion flows beneath a source of ultra-violet rays 5 comprising a quartz tube 6 mounted in a hood 7. This hood is open at the bottom and provides reflectors 8 for directing the ultra-violet rays downward against the stream of emulsion passing beneath.

The treated emulsion is discharged into a trough 9 whence it is pumped by a pump 10

through a pipe 11 having a valve 12 therein. The pipe 3 communicates with the discharge of the pump and provides a valve 13 for controlling the flow therethrough. A batch of 5 emulsion may thus be recirculated until completely treated after which the treated emulsion may be pumped through a pipe 14 into a settling tank 15, the flow through this pipe being controlled by a valve 16. The water 10 particles of the emulsion are sufficiently agglomerated under the influence of the ultra-violet rays so that the water readily separates from the oil in the settling tank, the former being withdrawn through a pipe 18 15 communicating with the settling tank and the latter being withdrawn through a pipe 19 communicating with the top of the settling tank.

A baffle 20 prevents undue turbulence in 20 the settling tank, due to the discharge of emulsion thereinto. A new supply of emulsion to be treated may be pumped into the system through a pipe 21 communicating with a storage tank 22 when a valve 24 25 therein is opened.

Such a batch process is sometimes necessary with emulsions which are difficult of treatment. However, many emulsions may be completely broken by passing under the 30 influence of the ultra-violet rays but once. In this event, a continuous process may be used by allowing the treated emulsion to pass directly from the trough 9 to the settling tank through a pipe 26, the flow being controlled by a valve 27.

The term "chemical system," as used in this disclosure and in the appended claims is not meant to include a chemical combination in the strictest sense of this latter term, 40 but rather a combination of chemical substances and should be so interpreted. These substances are usually present in the system as a mixture rather than forming a chemical combination.

45 By "rays of short wave length," as the term is used in the appended claims, I mean rays of the order of wave length between the extremes comprised in the rays emitted by ordinary X-ray tubes, quartz mercury-vapor lamps, or known radioactive elements.

50 I claim as my invention:

1. A process of separating a disperse chemical system into its constituent phases, which includes the step of subjecting said system to the action of rays of short wave- 55 length.

2. A process of separating a disperse chemical system into its constituent phases, which includes the steps of: subjecting said 60 system to the action of rays of short wave-length; and utilizing the difference in density of said phases for separating said phases.

3. A process of separating a disperse 65 chemical system into its constituent parts,

which includes the step of subjecting a stream of the substance forming said system to the action of rays of short wave-length.

4. A process of separating a disperse chemical system into its constituent parts, 70 which includes the steps of: subjecting a stream of the substance forming said system to the action of rays of short wave-length; removing said stream of said substance from the influence of said rays; and gravitationally separating said phases. 75

5. A process of separating the phases of a petroleum emulsion, which includes the steps of: subjecting said emulsion to the action of rays of short wave-length; and separating said phases. 80

6. The method of separating disperse systems into their component phases which comprises irradiating such systems for a substantial length of time under conditions favoring the passage of the rays through the system, the irradiating rays being of wave lengths comprised between the extremes of wave lengths of the kinds emitted from ordinary X-ray tubes, quartz mercury-vapor 85 lamps and known radioactive elements, and then allowing the phases to separate on standing. 90

7. A method according to claim 6 in which the disperse system is an emulsion. 95

8. A method according to claim 6 in which the disperse system is a naturally formed petroleum emulsion.

9. The method of separating the phases of a disperse system which comprises irradiating the mixed system by the light of a quartz mercury-vapor lamp for a substantial period of time and then allowing the phases to separate by standing. 100

In testimony whereof, I have hereunto set 105 my hand at Los Angeles, California, this 8th day of April, 1929.
